HONING ELEMENT

William G. Crowe, Brighton, Mich., assignor to Mid-West Abrasive Company, Owosso, Mich., a corporation of Delaware

Filed July 2, 1963, Ser. No. 292,337
10 Claims. (Cl. 51—204)

This invention relates generally to a honing assembly and refers more particularly to the honing elements for such an assembly.

One object of this invention is to provide honing elements for a honing assembly which are capable of being inexpensively manufactured and yet which are extremely efficient in the performance of its intended function.

Another object is to provide a honing element which is designed to have a maximum cooling effect.

Another object is to provide a honing element so constructed as to provide a pocket or pockets which serve as a reservoir for coolant.

Another object is to provide a honing element composed of an elongated abrasive stick and a holder for the stick having non-abrasive tabs at the ends of the stick which tabs are narrower than the stick to provide pockets or reservoirs for the cooling medium.

Other objects and features of the invention will become apparent as the description proceeds, especially when taken in conjunction with the accompanying drawing, wherein:

FIGURE 1 is a side elevational view of a honing head equipped with the honing elements of this invention.

FIGURE 2 is a side elevational view of one of the honing elements.

FIGURE 3 is an end view of the honing element.

FIGURE 4 is a top plan view of the honing element.

FIGURE 5 is a sectional view illustrating the adjusting member of the honing head in engagement with one of the honing elements.

FIGURE 6 illustrates a modified honing element in end elevation.

Referring now more particularly to the drawing and especially to FIGURES 1-5, the honing tool is semi-diagrammatically indicated at 10 and comprises an elongated tubular head 12 which has a plurality of circumferentially spaced slots 14 elongated in the direction of length of the head. Honing elements 16 of identical construction are respectively disposed in the slots for radially in and out movement.

Each honing element 16 comprises an elongated holder 18 and an elongated bonded abrasive stick 20 of uniform rectangular cross-section throughout its length. Actually, the cross-section may not be quite rectangular because the working face 22 of the abrasive stick will become crowned somewhat in use due to contact with the cylindrical surface of an internal bore being honed.

The holder 18 has an elongated base 24 provided with a flat front face 26. The back surface 28 of the base is inclined as shown in FIGURE 2 for reasons which will become more apparent as the description proceeds.

The abrasive stick extends lengthwise of the base of the holder and is secured to the front surface 26 thereof by a suitable cement. The width of the stick is the same as the width of the base and therefore the flat parallel sides 30 of the stick are flush with the flat parallel sides 32 of the base. FIGURE 6 illustrates a modification

2

which differs only that the thrust or trailing side of the stick has a non-abrasive coating 33 which may be an epoxy resin coating and which is flush with the corresponding side of the base to reduce or prevent slot wear.

5 The holder also has tabs 34 and 36 which project from the front surface 26 of the base at the ends thereof, which tabs are formed integrally with and of the same material as the base. The tabs extend along the ends of the stick in abutting relation therewith. The 10 cement for permanently securing the stick to the front surface 26 of the base may also be applied to the ends of the stick and to the tabs where these members contact one another so that there is also an adhesive bond between the tabs and the stick.

15 The tabs 34 and 36 will be seen in FIGURES 3 and 4 to be narrower than the base and also narrower than the stick. Thus the tabs will be observed to be centered with respect to the stick. The flat front surface of the base extends beyond the ends of the stick to the extreme ends 20 of the base on both sides of each tab. The base and tabs are rounded somewhat at the ends to conform more or less with the outline of the slots. The front faces 38 and 40 of the tabs are disposed in the plane of or flush with the front working face 22 of the stick. As seen in 25 the drawing, these front faces 38 and 40 provide extensions of the working face of the stick. There is little, if any, gap between the front working face of the stick and the front surfaces of the tabs because of the substantially abutting relationship therebetween. The front faces of the tabs will wear with the stick and hence will have the same contour as that of the stick which may be slightly rounded or crowned after use.

30 The holder 18 may be formed of any one of a number of materials depending to some extent on the character 35 of the abrasive sticks. Metal is preferred, and such metal as magnesium or aluminum or alloys containing these metals are generally suitable for use in connection with most types of abrasive sticks. Actually, it would be possible to fabricate the holder from various resins, preferably thermosetting, such for example as a phenolic resin. In any event a material is selected which possesses the required strength and has a wear resistance no greater than that of the abrasive stick. Ordinarily, the holder 40 has a wear resistance approximately equal to that of the stick so that the tabs will wear at the same rate as the stick. Accordingly, the surfaces 38 and 40 of the tabs will remain flush with the outer working face 22 of the stick, and the surface 38 of the tab 34 may be used as a gauging surface for determining the diameter of the abrasive head 50 by a gauging device 42.

55 It was stated that a metal holder is preferred. Metal has been found to be of a more porous nature than plastic. The greater porosity of the metal holders, especially at the front or outer surfaces of the tabs, acts to entrap 60 coolant and results in a more uniform breakdown or wear when in contact with the workpiece.

65 The gauging device 42 is indicated generally in FIGURE 1 and is not shown in greater detail because it forms no part of the invention. It will be sufficient to point out that the gauging device is applied to the honing tool 10 and has radially adjustable shoes which are contacted by the tab surfaces 38 when the head 12 is moved to its uppermost position relative to the work. Since the tabs wear uniformly with the stick, engagement of the surfaces 38 of the several honing elements with the gauging

device affords an accurate measurement of the effective diameter of the honing assembly.

Guide elements (not shown) of fibre or other similar material are supported on the head 12 between the abrasive elements in order to position the head when the abrasive elements are collapsed.

In accordance with conventional practice the honing elements are supported in the slots 14 of the head and have sufficient frictional engagement with the side walls of the slots to prevent them from dropping out when the head is retracted from the bore. An adjusting member 45, which is cone-shaped, moves axially within the head and contacts the inclined inner surfaces 28 of the holders to move the honing elements radially outward into contact with the bore. In operation, the honing head reciprocates within the bore and at the same time rotates to abrade the surface of the bore. As the head moves on its upward stroke the surfaces 38 of the upper tabs move within the gauging device.

It is preferred to coat the trailing or thrust side of each abrasive stick (FIGURE 6) because in use the trailing side engages the slot wall under substantial pressure, and an exposed trailing side would have a substantial abrading action.

The tabs 34 and 36 are substantially narrower than the abrasive stick of each honing element, and the tabs in cooperation with the ends of the stick and the front surface 26 of the base define pockets, designated 50, which serve as reservoirs for the cooling medium. The cooling medium may be introduced into the bore at the top during the honing operation. The coolant not only keeps the temperature within satisfactory limits, but also serves to keep the stones clear and flushed of the honing silt, that is the particles of metal, abrasive, bond, or any foreign material in the bore. This honing silt may collect on the working face of the stick and form a glaze over it unless there is sufficient coolant to flush the silt and to prevent the silt from getting hot enough to form a glaze. The amount of coolant that can be maintained in contact with the honing elements, and particularly with the working faces of the abrasive sticks, has been found to be greatly increased by the pocket construction of the abrasive elements. The pockets collect the coolant and provide a reservoir from which it spreads directly over those surfaces of the stick and holder which contact the work. The cooling medium also moves directly from the pocket reservoirs along the leading edges of the working faces of the sticks.

Probably the most important pocket is the one formed by the upper tab 34 adjacent the leading edge of the abrasive element, which pocket is designated 52. By the leading edge is meant that edge of the stone which faces toward the direction of rotation of the honing head. Arrow 53 indicates the direction of rotation. Pocket 52 provides a reservoir from which coolant can move directly down along the leading edge of the stick. This side or edge of the stick is exposed, in both the FIGURES 1-5 and FIGURE 6 embodiments, and accordingly the coolant moves readily over the working face. The pocket at the opposite side of the upper tab, that is at the trailing or thrust side, also collects coolant which is distributed down the trailing edge of the abrasive element and likewise facilitates the flushing of silt from the abrasive elements and from the regions adjacent thereto. The pockets formed on either side of the lower tab also collect coolant during the down stroke, which is distributed along the leading and trailing edges particularly during the up stroke.

Heretofore, the coolant introduced at the top of the bore either ran directly down the walls of the bore in no special relationship to the honing elements, or was thrown off by centrifugal force and the full benefit of the coolant was not realized. The pocket construction of the honing elements provides, in effect, restrictions which collect the coolant in reservoirs located in close proximity

to the critical trailing and leading edges of the abrasive stick and from which the coolant can be discharged along those edges for maximum cooling and flushing efficiency.

Sometimes in the past it has been necessary to force the honing elements outward under considerable pressure in order to break down the glaze over the abrasive so that fresh abrasive could be presented to the work. Honing elements constructed according to the present invention provide a sufficient increase in the amount of coolant over the working faces of the honing elements that the silt is flushed away before a glaze can form.

What I claim as my invention is:

1. A honing element for a honing tool, comprising a substantially rectangular bonded abrasive stick, and an elongated holder therefor having an elongated base of substantially the same width but of greater length than said abrasive stick, the front of said elongated base being provided at opposite ends thereof with forwardly projecting integral tabs disposed at opposite ends of said abrasive stick and having a width less than said base and less than said abrasive stick, said base being provided between and upon opposite sides of said tabs with a flat front surface whereby the portions of the flat surface upon opposite sides of said tabs in cooperation with said tabs and the opposite ends of said abrasive stick provide pockets for the reception of a cooling medium, the rear surface of said abrasive stick being secured to the flat front surface of said elongated base, the front surface of said abrasive stick being substantially flush with the forward ends of said tabs.

2. The honing element defined in claim 1, wherein the tabs abut and are secured to said abrasive stick.

3. The honing element defined in claim 1, wherein the base and the tabs have rounded ends flush with each other.

4. The honing element defined in claim 1, wherein the holder including the base and the tabs are formed from metal, and said holder has a wear resistance approximately equal to that of said abrasive stick, whereby said tabs are adapted to wear at the same rate as said abrasive stick.

5. The honing element defined in claim 1, wherein at least one side edge of said abrasive stick has a non-abrasive coating substantially flush with the corresponding edge of said base to reduce wear.

6. The honing element defined in claim 1, wherein at least one side edge of said abrasive stick is uncovered and is exposed.

7. The honing element defined in claim 1, wherein the holder including the base and the tabs are formed from resinous material.

8. A honing element for a honing tool, comprising a substantially rectangular bonded abrasive stick, and an elongated holder therefor having an elongated base extending lengthwise of and being of greater length than said abrasive stick, the front of said elongated base being provided at one end thereof with a forwardly projecting tab disposed at one end of said abrasive stick and having a width less than said base and less than said abrasive stick said base being provided with a flat front surface to which the rear surface of said abrasive stick is secured, said flat front surface having a portion extending upon one side of said tab, said portion of said flat front surface in cooperation with said tab and said one end of said abrasive stick providing a pocket for the reception of a cooling medium, the front surface of said abrasive stick being substantially flush with the forward end of said tab.

9. The honing element defined in claim 8, wherein said flat front surface has a second portion extending upon the opposite side of said tab, said second portion of said flat front surface in cooperation with said tab and said one end of said abrasive stick providing a second pocket for the reception of a cooling medium.

10. A honing element for a honing tool, comprising a substantially rectangular bonded abrasive stick, and an elongated holder therefor having an elongated base extending lengthwise of and being of greater length than said abrasive stick, the rear of said stick being secured to the front of said base, said base having at one end thereof a forwardly projecting tab disposed at one end of said abrasive stick, said tab having a width less than said base and less than said abrasive stick to provide a pocket which is open at the side of said honing element and at the front thereof for the reception of a cooling

medium, the front surface of said abrasive stick being substantially flush with the forward end of said tab.
